UNITED STATES PATENT OFFICE.

ORREN D. PURINGTON, OF PROVIDENCE, RHODE ISLAND.

IRONING-MACHINE.

1,100,096.

Specification of Letters Patent. Patented June 16, 1914.

Application filed December 2, 1913. Serial No. 804,169.

To all whom it may concern:

Be it known that I, ORREN D. PURINGTON, a citizen of the United States, residing at 115 Cole avenue, Providence, in the county 5 of Providence and State of Rhode Island, have invented certain new and useful Improvements in Ironing-Machines, of which the following is a specification.

My invention relates to an ironing device, 10 and has for its objects the smoothing of the surfaces of neckties, after the same have become wrinkled by use; and to render the mechanism employed simple to operate, and adaptable to operation upon articles of varying thicknesses.

To the above ends primarily my invention consists in such parts and combinations of parts as form the subject matter of the appended claims.

20 In the accompanying drawings which form a part of this specification Figures 1 and 2 are front and end elevations respectively of my novel device, Fig. 3, a vertical section of the same on line $x-x$ of Fig. 2, 25 Fig. 4, a section on line $y-y$, of Fig. 1 and, Fig. 5, a bottom plan view of the presser foot.

Like reference characters indicate like parts throughout the views.

30 My device includes a frame, comprising a post 2 and an upright 3. Upon the post is an integral extended hub or sleeve 4, in which is journaled the shaft 5, extending through an opening 6 in the upright 3, in 35 which it also has a bearing. Fixed to the shaft 5 is a crank 7, provided with a handle 8. Fast on shaft 5 is a drum 11, provided in its periphery with a cavity 12, at the base of which is fixed a hook 14. Near the top 40 of the members 2 and 3 are screws or pins 17 passing through openings 19 in ears 20, extending upwardly from a housing 21, comprising side pieces 22 and a top cross-piece 23. The housing, therefore, depends 45 from and is pivoted upon the members 17 and a presser foot 24 is slidably mounted in the lower portion of the housing or guide and is adapted to contact with the periphery of the drum 11.

50 In detail the presser foot 24 comprises an upright portion 25, and an arcuate laterally extending portion or toe 26, to whose outer end is fixed a finger piece or handle 28. The portion 25 of the presser foot is rectangular and has a sliding fit in the housing. To its

upper surfaces is fixed by screws 30, or otherwise the lower end 31 of a flat spring 32, whose upper end 33 is fixed by screws 34 or otherwise to the cross-piece 23, of the housing. The spring 22, in the present instance a folded spring, normally presses the foot 24 toward the drum. The lower or contacting face of the presser foot is provided with a series of parallel transversely disposed V-shaped ribs or corrugations 36 65 whose apices are in alinement with each other longitudinally of the foot and at an equal distance from the sides thereof, as shown in Fig. 5, wherein the arrow indicates the direction of travel of the article 70 to be pressed.

In Figs. 2 and 4 is shown the necktie 38, having its forward end engaged in the hook 14, with its intermediate portion resting upon the drum beneath the presser foot. 75 The drum is operated in the direction of the arrow shown in Fig. 4, advancing the necktie in contact with the bottom face of the presser foot which in turn is pressed into engagement with the tie by the spring 32. 80

When it is desired for any reason to free the tie, the member 24 may be elevated into inclined position as shown in dotted lines in Fig. 4 by manually lifting the handle 28.

85 What I claim is,

1. In an ironing machine, the combination with the frame, of a drum rotatably mounted in the frame, a guide pivotally mounted in the frame adjacent the drum, a shoe comprising a body portion slidably mounted in 90 the guide, and a laterally extending bearing portion adapted to engage the drum.

2. In an ironing machine, the combination with the frame, of a drum rotatably mounted in the frame, a guide pivotally mounted in the frame above the drum, and a shoe comprising a body portion slidably mounted in the guide, a laterally projecting bearing portion adapted to coöperate with the face of the drum, and V-shaped ribs 100 upon the operating face of the shoe whose apices are disposed in a direction opposite to the direction of rotation of the drum.

In testimony whereof I have affixed my signature in presence of two witnesses.

ORREN D. PURINGTON.
